UNITED STATES PATENT OFFICE.

JOHN THOMAS TEBBUTT, OF THREE RIVERS, QUEBEC, CANADA.

MANUFACTURE OF SHOES.

1,011,668.

Specification of Letters Patent. Patented Dec. 12, 1911.

Application filed June 3, 1909. Serial No. 500,000.

To all whom it may concern:

Be it known that I, JOHN THOMAS TEBBUTT, resident of the town of Three Rivers, in the Province of Quebec, in the Dominion of Canada, a subject of the King of Great Britain, have invented certain new and useful Improvements in the Manufacture of Shoes; and I do hereby declare that the following is a full, clear, and exact description 10 of the same.

The invention relates to the manufacture of shoes, as described in the present specification and illustrated in the accompanying drawings that form part of the same.

15 The invention consists essentially in arranging and attaching the various soles and generally constructing the shoe in a manner hereinafter described and particularly pointed out in the claim.

20 The objects of the invention are to devise a shoe in which the construction thereof will insure a perfectly dry foot should the shoe be fairly well worn down, to keep the foot in a perfectly sanitary condition, to keep the 25 foot warm and comfortable within the shoe and generally to provide a substantial form of footwear without materially increasing the cost of production.

20 In the drawings, Figure 1 is a perspective view of the bottom portion of the shoe, showing parts of the outsoles in longitudinal and cross section and an additional sole therebeneath turned over. Fig. 2 is a cross sectional view of the various soles and upper attached thereto, on the line A—B in Fig. 1. Fig. 3 is a cross sectional view of the arrangement of the heel portion on the line C—D in Fig. 1.

40 Like numerals of reference indicate corresponding parts in each figure.

In the manufacture of this shoe, the insole 1 is split inwardly from the edge faces forming the upper lip 2 and the lower lip 3, the welt 4; the upper 5 and the lower lip 3 are then attached together by the stitching 6. The water proofing 7 composed of suitable ingredients is now applied on the bottom of the insole in the corner formed by the lower lip 3 so that the stitching 6 is completely covered by said water proofing compound. The next step in this method of manufacturing the shoe, is to form a woven asbestos sole 8 and it is important that this sole should be of said material and of a size 5 to fit over the waterproofing, the said sole 8 terminating adjacent to the end of the

lower lip 3 and rearwardly extending under the heel portion of the insole being met at the sides and end by the upper 5. The woven asbestos sole 8 is attached to the insole 1 by 60 a wheat flour paste 9, said flour paste being extremely essential in this construction as an adhesive for securing said soles together eliminating all the deteriorating effects of other substances which might be used and 65 which are so close to the foot of the wearer.

The asbestos sole 8, the insole 1 and the lining 10 are all impregnated with an antiseptic compound preferably a compound of which eucalyptus is the principal ingredient. 70 The sole 11 is then suitably shaped and molded and secured to the welt 4 by the stitching 12. It will be thus seen that a complete outer sole is now provided stitched to the welt as customary in shoe making, but 75 in order to add to the stability of the shoe and insure the serviceability of the same, a sole 13 is shaped similarly to the sole 11 and a sole 14 shaped similarly to the soles 11 and 13. The soles 13 and 14 are cemented together and molded to fit to the sole 11. The three soles and the welt 4 being firmly secured together by the stitching 15, the lifts of the heel 16 are then secured in place and the shoe is complete. The introduction of the double sole in the manner described is a feature which tends to make this shoe perfectly dry, even when the lower outer sole or even the middle outer sole is worn, the single stitching still holding the 80 upper outer sole, the said upper outer sole with the rest of the shoe forming in themselves a complete shoe, the same as far as the outer sole is concerned as are at present manufactured. It is possible, of course, to add 85 to the lifts of the sole as is also constantly done, but when these lifts are independently attached to the upper lift and the welt and to one another, the said lower lifts become a separate wearing portion of the shoe instead of what is commonly known as an integral outer sole formed of a plurality of lifts.

An important feature of this invention is the impregnating of the inner sole and the 90 asbestos filling with an eucalyptus compound, which method provides, next to the foot, a thoroughly antiseptic support. Another important feature is the method of applying the waterproof compound, namely by 95 plastering the same into the corners of the insole formed by the downturned portion

through which the ~~stitch~~ ^g 6 extends, thereby effectively stopping the inner ends of the stitch holes by a solid mass of compound and preventing the entrance of water through said stitch holes.

What I claim as my invention is:

The improvement in the method of manufacturing shoes having an asbestos filler, consisting in impregnating the asbestos filler and also the inner sole with an eucalyptus compound, packing into the corners of the insole formed by the downturned portion through which the welt stitching extends a waterproof compound, thereby stopping the

inner ends of the stitch holes with a solid 15 mass of waterproofing, then sticking the filler to the insole with the waterproof compound as a boundary, then blocking into shape a plurality of outer soles and stitching them together and to the welt, and 20 finally finishing the heel portion of the shoe.

Signed at the town of Three Rivers, in the Province of Quebec, in the Dominion of Canada, this 1st day of June 1909.

JOHN THOMAS TEBBUTT.
